(57) **CLAIM**

The ornamental design for a toilet bowl, as shown and described.

DESCRIPTION

FIG. 1 is a perspective view of front, top and right side of a toilet bowl according to our new design;

FIG. 2 is a perspective view of rear, top and left side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged cross sectional view at 9-9 thereof; and,

FIG. 10 is an enlarged cross sectional view at 10-10 thereof.

The portions of the article in broken lines are shown for illustrative purposes only and form no part of the claimed design.
